UNITED STATES PATENT OFFICE

GEORGE E. PICKUP, OF NEWARK, OHIO, ASSIGNOR TO THE WEHRLE COMPANY, OF NEWARK, OHIO, A CORPORATION OF OHIO

SOLID-FUEL STOVE

Application filed June 3, 1929. Serial No. 367,848.

The invention relates generally to solid fuel burning stoves, and more particularly to a new and improved hinge support and counterbalancing means for the oven door of a stove adapted to burn coal, wood, coke, peat, etc.

Stoves or ranges adapted to burn solid fuel are commonly constructed with a firebox at one side and extending substantially the full 10 depth of the oven, with the space immediately over the firebox and oven constituting a combustion chamber. The side of the stove opposite the firebox is customarily provided with a water lagging or reservoir. This 15 standard arrangement has resulted from considerations of economy of space, accessibility, appearance and ease of operation.

The oven is provided with a door pivotally supported on hinges on the front of the stove. 20 Counter-balancing means is commonly employed, and usually consists of torsion springs coiled about the hinge members. This construction is exceedingly bulky and mars the appearance of the front of the 25 range.

The primary object of the invention is to provide a novel hinge support for the oven door, all parts of which are located rearwardly of the front surface of the stove.

Still another object of the invention is to provide a new and improved hinge support for the oven door of a solid fuel burning stove and counter-balancing means therefor which is located at the side of the oven remote 30 from the fire box to protect same from the heat, and which is concealed to improve the appearance and general contour of the stove.

Another object of the invention is to provide novel counter-balancing means for the 40 oven door which is so located that it will be readily accessible for purposes of replacement or repair.

Further objects and advantages of the invention will be understood from the following detailed description taken in connection 45 with the accompanying drawings, in which:

Figure 1 is a view in front elevation of a stove embodying a preferred form of the invention.

Fig. 2 is a fragmentary horizontal sec-

tional view taken along the line 2-2 of Fig. 1.

Fig. 3 is a fragmentary view showing the right hand trunnion and the counter-balancing means in elevation.

Fig. 4 is a fragmentary side elevation of the stove illustrated in Fig. 1.

The invention in certain of its aspects is applicable to various types of stoves, but is particularly advantageous in stoves burning 30 solid fuels, such as coal, coke, peat, or wood, and hence is illustrated in connection with a stove of this character.

Referring more particularly to the drawings, the stove illustrated comprises a base 10 having a plurality of supporting legs 11, and a superstructure mounted thereon. The structure forms an oven 12 substantially over the center of the base 10, a fire box 13 adjacent one side of the oven, and a flue space 70 leading from the box over the oven. The upper wall of the flue space constitutes a suitable top hot plate or cooking surface 14.

On the side of the oven 12 opposite the fire box is optionally mounted a water reservoir 16, the upper surface 17 of which is substantially flush with the top surface 14 of the stove, and adapted to constitute an extension thereof providing a side shelf for utensils. The fire box and oven are provided respectively with hinged doors 18 and 19. The door 18 preferably is mounted to swing about a vertical axis substantially along its left edge as viewed in Fig. 1. Any suitable form of hinge support may be utilized for the fire box door 18, and in the present instance a pintle and gudgeon type is employed for the reason that its parts may be so arranged as to be within the stove when the door is in its closed position, thus not detracting from the 80 appearance of the front of the range.

The oven 12 has suitable side walls 20 and 21, the former being adjacent the fire box. An outer wall 22 is provided in spaced relation to the wall 21 to improve the heat retaining properties of the oven. Secured to the front of the oven is a suitable door frame 23 defining a flanged opening 24 in which the door 19 is adapted to be located when closed. The side of the frame 23 remote from the 90 95 100

fire box 13 is channel-shaped in cross-section, having legs 25 and 26 secured respectively to the walls 21 and 22.

The door 19 is adapted to swing open and closed about an axis substantially coincident with its bottom margin. To this end, the door is provided with trunnions 27 and 28 on opposite ends, the trunnion 27 being journaled in the left wall of the frame 23 and the trunnion 28 being journaled in the legs 25 and 26 of the right wall of the frame and extending therethrough. The trunnions are secured as by means of bolts 29 in recesses or insets 30 formed in opposite ends of the lower marginal edge wall of the door.

Thus, the pivotal mounting for the door is not exposed as is customary, but is enclosed within the door frame 23, thereby improving the appearance of the front of the range, and permitting the counter-balancing means hereinafter described to be located rearwardly of the front.

Suitable counter-balance means is provided for the door 19. This means is so located that it will not be exposed or subjected to intense heat. To this end, it is mounted adjacent and outside of the double right end wall of the oven 12. Obviously the counter-balance means is protected from the heat in the oven by the double walls 21 and 22, and also from the intense heat of the fire box by reason of its remoteness therefrom.

To improve the appearance of the stove and also to avoid hindrance in opening and closing the door, the counter-balance means is located rearwardly of the door 19.

Preferably the counter-balance means comprises a rearwardly projecting lever arm 31 nonrotatably secured to the outer end of the trunnion 28. In this instance, the trunnion 28 is provided with a squared end which fits in a complementary hole in one end of the lever arm 31 and a headed screw 32 is provided to retain the parts in assembled relation. A contractile spring 33 is secured at one of its ends to the free end of the lever arm, and is anchored at its other end to the base of the stove as by means of a laterally extending hook bolt 38. The spring 33 acts in a direction tending to move the door into closed position.

To protect the spring 33 and its associated parts from injury, they are enclosed in a housing 34 preferably extending the entire depth of the stove. The housing 34 in effect constitutes a right end extension of the oven under the reservoir, and is shaped to harmonize with the general contour and design of the range. The housing 34 is in the form of a plate secured along its upper edge to the wall 22, then curving outwardly away from the wall, and then extending downwardly to the base 10. The ends of the plate are curved inwardly to the wall so that the plate and

wall define a closed chamber 36 for confining the counter-balance means.

The lower end of the front of the casing recedes rearwardly to define a recess 37. A vertical front cover plate 35 in the plane of the front of the stove extends across the front end of the reservoir 16. The lower end of the plate is reduced in size and is curved rearwardly to project into the recess 37. Thus when the reservoir is in position on the range its front casing completely covers the spring chamber thereby presenting a single continuous surface to view which lies substantially in the plane of the front of the stove. With the reservoir removed the spring chamber is exposed to view and lends itself to the general form and pleasing appearance of the range as a whole.

The counter-balancing means is so remotely situated with respect to the firebox as not to be impaired by heat and it is, at the same time, shielded from view and guarded from accidental injury.

By positioning the oven door trunnions rearwardly of the front surface of the range the use of bulky external hinges is avoided and the appearance of the stove as a whole is greatly enhanced.

I claim as my invention:

1. In a stove, in combination, a base, an oven on said base having side walls, a fire box adjacent one of said side walls, a water reservoir adjacent the other of said side walls, a door frame on the front of said oven, a door in said frame, said door having laterally projecting trunnions at its lower edge journaled respectively in the side walls of said frame, a lever secured to the trunnion remote from said fire box and extending rearwardly therefrom, a tension spring anchored to said base at a point rearwardly of said lever and secured to the free end of said lever, a housing enclosing said lever and said spring, said housing being disposed beneath said reservoir and secured to the adjacent side wall of said oven, and a cover plate mounted in front of said reservoir and said housing.

2. In a stove, in combination, a base, an oven on said base having side walls, a fire box adjacent one side wall, a door frame on the front of said oven, a door in said frame, said door having laterally projecting trunnions at its lower edge journaled respectively in the side walls of said frame, the trunnion remote from said fire box extending through the wall in which it is journaled, a rearwardly extending lever secured to the projecting end of said remotely located trunnion, a spring anchored at a point rearwardly of said door and secured to the free end of said lever, and a housing detachably secured to the outer side of said last mentioned side wall and enclosing said lever and said spring.

3. In a stove, in combination, an oven hav-

ing side walls, and an opening at the front thereof, a door mounted in said opening, said door having trunnions extending from opposite ends on a line substantially coincident with its lower margin, said trunnions being pivotally mounted in said side walls, one of said trunnions extending through its side wall, a counter-balancing mechanism operatively connected to said last mentioned trunnion and disposed rearwardly of said door and adjacent the outside of said last mentioned side wall, and a housing enclosing said counter-balancing mechanism and detachably secured in position to permit inspection of said mechanism.

4. In a stove, in combination, an oven having side walls, and an opening at the front thereof, a door mounted in said opening, said door having trunnions extending from opposite ends on a line substantially coincident with its lower margin, said trunnions being pivotally mounted in said side walls, a fire box adjacent one side wall, one of said trunnions extending through the other side wall, a spring actuated counter-balancing mechanism operatively connected to said last mentioned trunnion and disposed rearwardly of said door and adjacent the outside of said last mentioned side wall, and a housing detachably secured on the outside of said other side wall and enclosing said counter-balancing mechanism.

In testimony whereof, I have hereunto affixed my signature.

35 GEORGE E. PICKUP.
